(57) **CLAIM**

The ornamental design for a panel with repeating scalloped pattern for wall or ceiling, as shown and described.

DESCRIPTION

FIG. 1 is a broken-away perspective view of a panel with repeating scalloped pattern for wall or ceiling showing my design;

FIG. 2 is a right side view thereof, which is a mirror image of the left side view;

FIG. 3 is a top view thereof, which is a mirror image of the bottom view; and

FIG. 4 is a front view thereof.

The broken line showing of environment in the drawings is included for the purpose of illustrating only and forms no part of the claimed design.
